METHOD FOR DRYING SHEET MATERIAL

Original Filed Jan. 8, 1920. 2 Sheets-Sheet 2

INVENTOR
OGDEN MINTON
BY *Carleton E. Shuey*
ATTORNEY

UNITED STATES PATENT OFFICE.

OGDEN MINTON, OF GREENWICH, CONNECTICUT.

METHOD FOR DRYING SHEET MATERIAL.

Application filed January 8, 1920, Serial No. 350,236. Renewed July 9, 1926.

The present invention relates to an apparatus and method for the drying of paper and other sheet materials.

My improved method consists in passing 5 the sheet material, which is to be dried, into a vacuum chamber through a liquid sealing medium which has no affinity for the material, subjecting it to heat to drive off its contained moisture and then passing the 10 dried material out of the chamber through a seal.

This method may be practiced by the use of various forms of apparatus, some of which are herein disclosed. In any form, however, 15 it is essential that the apparatus be provided with a closed chamber in which a partial vacuum may be maintained. In order that the material to be dried may be continuously passed through the vacuum chamber, the latter 20 is provided with openings closed to the admission of air by a liquid sealing medium which has no affinity for the material. The liquid seal effectively closes the entrance and exit passages against the admission of air to 25 the chamber, but permits the passage of the material into and out of the chamber. The form of the heating elements within the vacuum chamber, for drying the material, the shape, form, dimensions and location of the 30 liquid seal containers, and the means for passing the sheet material through the chamber, may all vary.

My invention further relates to drying said sheet material by letting it pass adjacent to but not in contact with a source of convected heat, while under little or no tension, the tension being only sufficient to pass the sheet material through the apparatus.

My invention further relates to passing 40 said sheet material through said vacuum chamber in folds or loops and subjecting one or more of the folds or loops to the action of convected heat to dry said sheet material at a low temperature. My invention further 45 relates to subjecting said sheet material while in said vacuum chamber to the action of a glowing member. My invention further relates to subjecting said sheet material while in said vacuum chamber to an electric heating member, either in the form of 50 plates or coils. My invention further re-

lates to placing one or more of these electric heating elements adjacent to the folds or loops of the sheet material while passing through the vacuum chamber.

55

My invention further relates to manufacturing paper wherein the fibers in the paper are not weakened and the size if the paper has been sized before drying, is not injured or damaged, due to the low drying temperatures at which I carry out my improved method.

60

My invention further relates to manufacturing colored paper and drying it without substantially impairing the coloring matter and mordants used in the paper. Among other advantages this insures that the paper will have bright colors which will be substantially uniform in different runs of paper, permitting matching of colored paper without any appreciable difference in tone or color.

65

My invention further relates to passing a web of wet paper, sized or unsized, into a vacuum chamber without breaking the vacuum, and there permitting the fibers of the paper to shrink and dry at random, forming a paper which is substantially as strong lengthwise of the sheet or web as across the said sheet or web.

70

My invention further relates to manufacturing imitation loft dried paper having a "cockled" effect.

75

My invention further relates to taking a web of wet paper, either from the wet end 80 of the paper machine, or from the sizing vat, or from a coloring apparatus, or coating or printing machine, and continuously passing the web of paper into and out of a vacuum chamber, without breaking the vacuum in 85 the chamber, and heating and drying said web of paper in said vacuum chamber by permitting the fibers to dry or shrink under little or no tension so as to obtain a stronger and better product.

90

My invention further relates to passing such web of paper adjacent to but not in contact with one or more electric heating elements mounted in the vacuum chamber.

95

My invention further relates to certain 100 steps and combinations of steps, also to certain elements and combinations of elements,

whereby the method or processes herein described may be carried out, as well as to certain details of construction and combinations all of which will be more fully hereinafter described in the specification and pointed out in the claims.

I have shown in the drawings, somewhat diagrammatically two different forms of apparatus which may be used to carry out my improved method, but it is to be distinctly understood that my invention is not to be confined to the particular form of apparatus shown by way of illustration.

In the accompanying drawings the same reference numerals refer to similar parts in the several figures.

Fig. 1 is a vertical diagrammatic section of one form of apparatus which may be used to carry out my improved process;

Fig. 2 is a vertical diagrammatic section of a modified form in which one seal is used instead of two;

Fig. 3 is a sectional view showing the terminal wire connected with the electric heater elements;

Fig. 4 is a sectional view of one form of regulator for rolls.

In describing my invention, I will describe it as applied to sheet material in the form of paper, though it is to be distinctly understood it is equally applicable to, and covers drying sheet material in the form of textile fabric, as for example drying such fabrics after they have been washed, or bleached, or dyed, or otherwise treated with a liquid of some description.

In the ordinary drying of a web of wet paper such high heat is used as to injuriously affect the fibers of the paper, and in case the paper is colored it will adversely affect the coloring matter and mordants used. Drying paper in the high temperatures used in ordinary practice often affects the size so that the resulting paper varies in quality, is not uniform, and is not a perfect product.

In ordinary practice the paper is dried under sufficient tension to cause the fibers of the paper to rearrange themselves which results in a sheet of paper which is not uniform in strength.

By my improved method I dry the paper at such low temperatures, and while the paper is under practically no, or very little, tension so that the fibers can shrink at random, which action is not materially prevented by the very low tension on the paper while it is being dried. This results in much stronger paper and one which is substantially as strong lengthwise of the sheet as it is crosswise of the sheet, the paper being a much better product in every way.

My improved method can be employed for either manufacturing high or low grade paper, or imitation loft dried paper, having

the same "cockled" effect as though the sheets had been cut, stacked and allowed to dry slowly for forty-eight hours.

The web of paper 1, either coming from the wet end of a paper machine, or from a sizing vat, is passed into and out of the vacuum chamber 2 in any suitable manner so that the vacuum in the chamber will not be broken. I have shown this vacuum chamber provided with seals 3 and 4 in which is a liquid medium 5 of any suitable material, which has no affinity for, and no deleterious effect upon, the sheet 1, whatever it may be.

The medium which I preferably employ is mercury though it is to be distinctly understood that any suitable medium, having the characteristics above mentioned, may be employed. I may for example use an amalgam, or an alloy, or any other suitable material which will satisfactorily seal the vacuum chamber 2 and permit the sheet material 1, passing into and out of said chamber 2, without being injured or affected in any manner and without breaking the vacuum.

The degree of vacuum in the chamber 2 may be regulated. Preferably I employ a vacuum of about 28 inches, though this may be varied without departing from my invention.

The web 1 is fed into the vacuum machine over the guide roll 6, under the submerging roll 7, over guide roll 8, and under the guide rolls 9, 9 and over the guide rolls 10, 10. While passing through the vacuum chamber 2, it is put under little or no tension; the tension is sufficient merely to pass the web through the chamber. Preferably, the web is fed through in folds or loops 11, 11.

Adjacent to the loops 11, 11, but not in contact with them, I mount one or more glowing members preferably in the form of electric heaters 12, 12. Preferably these electric heaters are mounted between the folds or loops 11, 11 as indicated in Fig. 1, but of course this arrangement may be varied without departing from my invention. The electric heaters 12 are connected to the bars 12^a, from which extend the wires 12^b, through the insulated packing 12^c, to the contact terminals 12^d. The distance between the folds 11, 11 and the electric heating members 12, 12 must be sufficient to permit free passage of the web of paper without coming in contact with the electric heating elements.

To insure minimum tension upon the paper during drying, I may use any ordinary means to decrease the tension due to moving the paper, as for example, by mounting the various rolls, in each of the forms illustrated, in ball bearings, and driving them by a friction device whereby the speed of the rolls may be regulated. One form of such device is illustrated in Fig. 4 wherein the rolls such as roll 9 is mounted in ball bearings contained in the housing 31, held

in place by suitably packed bolts 32 passing through the wall 2 of the vacuum chamber. The pulley 33, preferably made of bronze, is mounted on, and revolves on, the shaft 34 of the roll 9. The portion of the shaft 34 upon which the pulley is mounted, is preferably made of Babbitt metal. Secured to the end of roll 9 and the side of the pulley 33 are two friction discs 35 and 36, made of any suitable material such as leather or woven asbestos tape. The pulley 33 is driven at constant speed by a belt 37. The small roll 38 is mounted in a housing 39, the position of which is regulated by the lever 40 actuated by the rod 41, passing through the packing gland 42 in the wall 2. The position of the rod 41 is regulated by the nut 43. The other end of the roll 9 will be mounted in a ball bearing housing similar to 31. The speed of roll 9 may be regulated, or its speed may be varied from a similar roll, by varying the pressure between the discs 35 and 36 by applying more or less pressure between the roll 38 and the pulley 33, which is driven at constant speed. As the friction between the discs 35 and 36 increases, the more nearly will the speed of roll 9 approach that of pulley 33.

The web of paper passing through the vacuum chamber will in this manner be dried, without placing any appreciable tension upon the web. What tension, as previously described, there is upon the web, is merely sufficient to pass it through the vacuum chamber and this tension does not appreciably interfere with the fibers of the paper drying at random, so that the resulting sheet of paper is as strong lengthwise of the sheet as it is crosswise.

In making imitation loft dried paper, this drying of the web within the vacuum chamber adjacent to, but not in contact with, the electric heaters 12, 12 and while under no appreciable tension causes the sheet or web to dry with the "cockeled" effect of genuine loft dried paper.

The dry web of paper 1, whether it be high or low grade paper or imitation loft dried paper, after passing between the different electric heaters 12, 12 is fed over the guide roller 13, and out of the vacuum chamber through the seal 4 under the submerging roller 14, over the guide roller 15, and is then preferably wound into a roll of finished paper 16.

In some cases, I may use one seal instead of two. I have shown such a construction in Fig. 2, in which the vacuum chamber 17 is provided with the same electric heaters 12, 12 and the same guide rollers 9, 9 and 10. Connected to the vacuum chamber is a hollow member 18, which dips into a liquid sealing member 19. The liquid 5 in this sealing member is the same as in the seals 3 and 4.

The web 1 is fed into the vacuum chamber 17 over the guide roll 20 under the submerging roll 21 and over the guide roll 22, and thence as indicated by the arrows, over and under the guide rolls 9, 9 and 10, 10 on the left of said figure, then over the guide roll 23 to the guide roll 24, mounted at the other end of the vacuum chamber, thence over and under the set of guide rolls 9, 9 and 10, 10 mounted on the right of said figure, all as indicated by the arrows, thence over the guide roll 25 and out of said vacuum chamber through the liquid seal 5 under the submerging roller 26 over the guide roll 27, and is then preferably wound into the complete dry finished roll of sheet material 28. The drying action in connection with the vacuum chamber 17 is the same as the drying action in vacuum chamber 2.

The vacuum chamber 2 is preferably provided with the windows 29, 29 and with the pipes 30, 30, which are connected to any suitable vacuum apparatus to maintain the desired vacuum within the vacuum chamber.

When the sheet material is a web of paper, from which imitation loft dried paper is to be made, the web 1 is taken from the sizing vat and then passed through the vacuum chamber in the manner previously described. When it emerges over the roller 15, it is dry, very strong, being substantially as strong lengthwise of the sheet as it is crosswise of the sheet and has the same "cockeled" effect as regular loft dried paper. It will be stronger than loft dried paper, however, for the reason that the fibers of the paper, as they originally came from the wet end of the paper machine in the form of a wet web of paper, were preferably dried by my method prior to being sized. The fibers of the paper were therefore, both when they were originally dried before being sized, and also after being sized, permitted to dry or shrink at random, and while not under sufficient tension to prevent them from so doing.

My method possesses many advantages not present in processes heretofore used for many years in the drying of paper.

The evaporation process, which is characteristic of the so-called loft drying of paper, has many fully recognized disadvantages, and yet it is used today and has been in use for many years. In this method the wet paper is taken from the paper machine, cut into sheets, hung on poles, carried to the drying room where it is subjected to hot air at about 130° F. for about 48 hours, and when dry, each sheet is separately calendered. Although possessing the advantage of drying at a comparatively low temperature, whereby the moisture is slowly evaporated, loft drying is obviously very inefficient and costly, because it requires many separate manipulations, is extremely slow, uses extensive floor space and wastes heat.

The process which is employed in the ordinary paper machine in common use, is likewise subject to many disadvantages. In such machine, the wet paper as it comes from the paper machine, is passed over many revolving cylinders, heated internally by steam to sufficiently high degree of heat, to raise the temperature of the water in the paper to 212° F., the atmospheric boiling point of water. It is customary to supply the drying cylinders with steam at approximately 5.3 pounds gauge pressure, at which the steam has a temperature of 228° F., giving a difference of temperature (228°-212°) of only 16° F. With this slight difference of temperature the transfer of heat is extremely slow, and hence it is necessary to employ many drying cylinders, in board machines often one hundred, and in news print machines, forty or more.

Also due to convection and conduction losses, as well as those incident to leaks in the piping system and other inefficiencies, the heat actually required for atmospheric drying of a ton of wet paper, is very much in excess of the theoretical requirement. The thermal efficiency of atmospheric drying by steam heated cylinders is therefore very low. Furthermore, the steam produced from boiling the water out of the paper, is driven off into the operating room, and although fans and exhausters are employed, at large expense for power and maintenance, the room atmosphere is so constantly saturated with moisture as to rust and ultimately destroy all iron and steel materials, and produces an exceedingly disagreeable and unhealthy atmosphere in which to work. It is well known that the minimum temperature 212°, the atmospheric boiling point of water, is positively injurious to, and results in oxidizing, the fibres of the paper, the strength of which is vastly improved when the paper is dried at lower temperatures, as in loft drying. This atmospheric drying process requires large initial cost for cylinders, felts, and other necessary equipment, and extensive floor space, and results in the consumption of large amounts of power, and great cost for operation, maintenance and repairs.

The thermal efficiency of my vacuum method is very much greater than that of the atmospheric cylinder drying heretofore in universal use for drying paper. Theoretically, it requires about 5287 pounds of steam to dry one ton of paper at atmospheric pressure, but to compensate for convection and conduction losses, and those due to leaks in the piping system, and other inefficiencies, it has been shown in practice that about 10,600 pounds are required.

In my method, using a vacuum of about 28", the convection, conduction and piping losses are exceedingly small and the total

steam required to dry a ton of paper by my method is approximately 5200 pounds.

It is an established fact that paper dried at low temperatures is much stronger than when it is dried at the high temperatures used in paper machine atmospheric drying. Paper dried in a vacuum of 28", or at a temperature of about 100° F., as in my method, is very much stronger than paper dried at atmospheric pressure, when the steam in the driers is at 228° F. When paper is dried by my method, therefore, a cheaper furnish or stock can be used and still produce a paper equal in strength to atmospheric dried paper, in which a higher grade furnish or stock is used. In making newsprint paper, I am able to dispense with a considerable portion of the more expensive sulphite pulp, as this can be replaced with the cheaper ground wood pulp.

Furthermore, in my method there is a great saving of heat (or steam) because the process is carried on in a vacuum chamber which acts on the principle of a thermos bottle, and the steam and vapors driven out of the wet paper are caught in the closed vacuum chamber, and conducted away to the condenser. The operating room is free from steam, humidity and heat, and fans, and exhausters are dispensed with. In the use of my method the apparatus is at all times operating under definite humidity, the control of the drying can be closely standardized, and the moisture content in the paper carefully regulated.

Having pointed out the many advantages of my method and apparatus over those heretofore used, it will be apparent that the use of my invention results in great economy in the initial cost of apparatus and in large savings in cost of operation, maintenance and repairs.

Having thus described this invention in connection with an illustrative embodiment thereof, to the details of which I do not desire to be limited, what is claimed as new and what is desired to secure by Letters Patent is set forth in the appended claims.

What I claim is:—

1. The method of drying a continuous web of paper coming from the wet end of a paper machine or from a sizing vat or from a coloring apparatus, coating machine or printing machine, consisting in continuously feeding the web of paper into and out of a vacuum chamber without breaking the vacuum, and without sufficient tension upon the web to cause its fibers to substantially rearrange themselves from the interlaced position assumed by them on the wire mesh of the paper machine, subjecting said web on its continuous passage through the vacuum chamber to radiant heat from an electric heater, so that the web of paper will be dried with its

fibers in substantially the interlaced position assumed by them on the wire mesh of the paper machine.

2. The method of drying a continuous web of paper coming from the wet end of a paper machine or from a sizing vat or from a coloring apparatus, coating machine or printing machine, consisting in continuously feeding the web of paper into and out 5 of a vacuum chamber without breaking the vacuum, and without sufficient tension upon the web to cause its fibers to substantially rearrange themselves from the interlaced position assumed by them on the wire mesh 10 of the paper machine, subjecting said web on its continuous passage through the vacuum chamber to radiant heat from an electric heater, so that the web of paper will be dried with its fibers in substantially the 15 20 interlaced position assumed by them on the wire mesh of the paper machine and then winding the dry web of paper into a roll

or reel of dry paper so that it can be run through a stack calender if desired.

3. The method of drying a continuous web of paper coming from the wet end of a paper machine or from a sizing vat or from a coloring apparatus, coating machine or printing machine, consisting in continuously feeding the web of paper into and out of a 25 vacuum chamber through one or more mercury seals and during its passage through said vacuum chamber and mercury seals placing only sufficient tension upon the web to insure its continuous passage, the tension 30 not being sufficient to cause its constituent fibers to substantially rearrange themselves from the interlaced position assumed by them on the wire mesh of the paper machine, and continuously heating and drying said 35 40 web while in said vacuum chamber by causing it to travel adjacent to but not in contact with one or more fixed electric heaters.

OGDEN MINTON.
